(57) CLAIM

The ornamental design for an article of footwear, as shown and described.

DESCRIPTION

FIG. 1 is a perspective photographic view of an article of footwear showing my new design;

FIG. 2 is a front photographic view thereof;

FIG. 3 is a rear photographic view thereof;

FIG. 4 is a left side photographic view thereof;

FIG. 5 is a right side photographic view thereof; and,

FIG. 6 is a top photographic view thereof.

The word mark "SOREL" shown in the figures is a registered trademark of Sorel Corporation. The word mark "SOREL" forms no part of the claimed design.
